WINDING MACHINE

Edward J. Abbott, Wilton, N. H., assignor to
Abbott Machine Company, Wilton, N. H., a
corporation of New Hampshire

Application February 9, 1935, Serial No. 5,730

6 Claims. (Cl. 242—38)

This invention relates to an improvement in mechanism responsive to breakage or exhaustion of one of several simultaneously handled strands, for automatically causing breakage or severance of the remaining accompanying strands, in processes such as doubling, twisting, winding or spinning.

A principal object of the invention is to provide, during the time winding is being started, a period in which failure of one strand to be put into or maintained in operative relation to the detecting or strand-responsive mechanism or element will not precipitate a breakage or severance of the remaining strands. The attainment of this object permits the operator of the machine to supervise the starting of winding with less attention to the relation of the several strands which are to be subject to the detecting operation, and particularly precludes the possibility of a premature or false actuation of the detecting mechanism and consequent breakage or severance caused by irregularity in the tensions or positions of the strands at the start of winding.

Although it will be apparent from this specification that the invention is of general applicability to mechanism for accomplishing the breakage or severance referred to above, the present invention will be explained by a description of its application to apparatus described and claimed in my allowed patent application Serial No. 693,116, filed October 11, 1933, now Patent No. 1,995,730, issued March 26, 1935.

Other objects of invention and features of novelty and utility will be apparent from this specification and its drawings, wherein the invention is explained by reference to preferred examples thereof.

In the drawings:

Fig. 1 is a front view of a traveling doubling unit of the aforesaid application, having the present invention incorporated therein;

Fig. 2 is a right side view of the unit of Fig. 1, parts of the frame and driving connections of the machine being shown in vertical section;

Fig. 3 is a view on line 3—3 of Fig. 2, showing the yarn guiding plate of the unit with strand detecting means mounted thereon;

Fig. 4 is a view at right angles to Fig. 3, on the line 4—4 of Fig. 2, showing the strand detector;

Fig. 5 is a view similar to Fig. 4, showing an element of the detector tilted part way toward its releasing position, but prevented from further tilting;

Fig. 6 is a view similar to Fig. 2, showing a modified form of the invention; and

Fig. 7 is a view on the line 7—7 of Fig. 6.

By way of example only, the invention is illustrated as embodied in a traveling multiple unit machine of the general construction shown in

Letters Patent of the United States No. 1,609,639,

as improved by the invention shown in my application Serial No. 476,776, filed August 21, 1930, and equipped with a pair of supply spindles for each unit for the purpose of doubling two strands, and further improved by the strand-breaking or severing mechanism of my application Serial No. 693,116.

Referring to Figs. 1 and 2, each unit may for example include an upright 10, having at its top a winding head 11 which is guided on an upper rail 12 by means of rollers 13 and 14, and on its lower part a suitable roller 15 guiding the upright 10 on a lower rail 16. The several units of the machine are conveyed in the direction of the arrow z (Fig. 1) in a closed path defined by the rails 12 and 16, by means of a chain 17 to which the respective units are attached by links 18.

The spindle 20 of winding package 21 may be carried by an arm 22 pivoted at 23 on the head in position for the package 21 to rest on a drive roll 26, extending along the machine. A suitable traverse cam 28 is mounted in the winding head in position to be driven by roll 26, and to reciprocate a traverse guide 29. The traverse cam 28 is preferably covered by a yarn-guiding cover plate 30, which extends from the path of the traverse guide 29 at a slight downward slope to the point 30^a (Fig. 2), and thence downward at a greater slope to its lowermost point 30^b. At its bottom, this cover plate 30 has a turned up portion 31 at right angles to the adjacent portions of the plate, as shown in Fig. 2, approximately in the plane of the supply package spindles 41.

As shown in Fig. 1, these supply package spindles 41 are mounted on a suitable bracket 42 to point or converge toward the approximate center of this upturned support 31 for the detector. Associated with member 31 are suitable guide means to receive the two strands x and y coming from the supply package, for example, a pair of slots 43, 44, through which the strands separately pass on their way to the traversing guide eye 29, and for the purpose of threading the strands onto these slots, the upper edge of member 31 is preferably downwardly inclined from both sides to these slots.

The winding speed of the mechanism may be, for example, 500 to 800 yards per minute, at which speeds the yarn coming freely off over the ends of the supply packages will exert a strong ballooning effect sufficient to tension the yarns. A separator plate 47 is accordingly recommended for controlling the balloon thus formed.

The detecting and breaking or severing mechanism disclosed in my said application Serial No. 693,116 includes a light tilting plate 50 having lateral ears 51, 52 (Figs. 3 and 4), each of which normally supports one of the two tensioned strands x and y as they pass through the slits 43, 44 of member 31.

The tilting plate is mounted, as indicated in Fig. 4, upon two pins 55, 56, extending from a supporting member 57, which as indicated in Figs. 3 and 4, is mounted on the plate 30 directly 5 behind the upturned flange 31. In the tilting plate 50, is a slot 58 formed in two arcuate portions of which the two pins 55 and 56 are the centers, the slot 58 receiving the two pins 55 and 56 and permitting the plate to tilt about either of the spaced pins 55 or 56 as a center. 10 The stationary supporting member 57 is provided with two guide ears 60, 61 having downwardly sloping tops adapted to direct laterally a strand laid in the slot 43 or 44, and thereafter adapted 15 to confine the strand against leaving the slot. In running position, therefore, the two strands each run through a slot 43 or 44 and rest on a lateral ear 51 or 52 of the tilting plate 50. If either strand fails, as by breakage or exhaustion, the strong tension on the remaining strand 20 tilts the plate 50 until the depressed one of the two ears thereon is withdrawn from the remaining strand. Thus, for example, when the plate 50 has been tilted to slightly beyond the tilted 25 position of Fig. 5, the strand *x* will be released therefrom.

Upon being released from the tilting plate 50, the unbroken strand is free to be pulled up its respective slot 43^a or 44^a by the winding tension, 30 until it assumes such an inclination to its supply package that it can no longer unwind over end from the package, and consequently breaks. The breaking or severance may also be accomplished or facilitated by the provision of knife-edges 81 35 or the like at the upper ends of the slots 43^a and 44^a, the strand being pulled against one of these knife edges by the tension.

Associated with the cover plate 30, there are preferably provided a pair of strand guides 70, 71, made for example, of wire, having inclined portions 70^a, 71^a adapted to engage two strands extending from the supply packages to the winding means and to lead them to a central throat defined by approximately parallel portions 70^b, 71^b. Such assembly of the strands in this throat can take place automatically while the operator allows the two strands to drop onto the opposite inclined edges of member 31, in position to be pulled into the front slots 43, 44. In normal running, the parallel portions 70^b, 71^b of the strand guides keep the two strands close together as they approach the reciprocating traverse guide 29, as shown in Fig. 3, but as shown in Fig. 2 the lower parts of these portions 70^b, 71^b terminate above 55 the cover plate 30, thus permitting the released strand *x* or *y* to travel up the appropriate one of the spaced slots 43^a or 44^a to breaking position. The preferred guides 70, 71 herewith illustrated, are thus shaped and disposed with reference to the breakage detector to bring together and center the strands between the detector and winding means, to retain them in this relation during normal winding, and release either strand which is released by the detector so that such 60 strand is free to assume its more direct path which induces breakage.

The particular strand detecting and breaking or severing mechanism described above is an example of the general class of such mechanism 70 to which the present invention is applicable. In such machine, after a replenishment operation or repair of a break, the most convenient way of getting the two strands into the detecting mechanism is for the operator to hold the two 75 strands which lead from the package 21 in one

hand and give the package a slight turn with her other hand to take up the slack, allowing the strands to be threaded into the detector. The package 21 is then automatically lowered into contact with the drive roll 26 by the operation 5 of the package lifting and lowering mechanism described in my application Serial No. 476,776.

However, in the event that the conditions of the two strands were so different that one strand was threaded into the detector and the other 10 still left outside the detector and in a slack condition, when the package began to be driven by the roll 26, the plate 50 of the detector might be tilted to releasing position before the other strand was drawn in, with the result that a false actuation 15 of the detector could occur. The present invention provides in mechanism of this general class, a period in which winding can start and any strand which has been left out of the detector can be drawn in, before the detector is 20 allowed to operate.

Figs. 1 and 2 show the unit at a position where its package has just been lowered to the drive roll by the mechanism and in the manner described in application Serial No. 476,776. At this 25 location in the path of travel of the units, there is mounted on a bracket 85, a narrow somewhat resilient metal strip 86 adapted to wipe across the flat top of the element 51 which pivotally supports the detector element 50 of the passing 30 unit, so as to overlie the detector element 50 and prevent it from fully tilting to a releasing position. Thus if during the beginning of winding one strand *x* should be in its slot 43 (Fig. 5) but the other strand *y* not yet have reached its slot 44, the 35 detector element 50 will be prevented from releasing strand *x*. The winding rotation of the package 21 will then be able to pull the strand *y* into its slot 44, and thereby put the detector 40 element 50 in balance before the detector element moves out from under the strip 86 and becomes operative.

In place of a form of means such as the above-described strip which is effective with respect to the several units of the machine in succession, 45 the modification of Figs. 6 and 7 provides a mechanism associated with each winding unit for accomplishing the same objects. Referring to these figures, the unit, like that of Figs. 1 to 5, is provided with the above-described detector 50 member 50 and associated parts adapted for strand-breaking or severing according to the invention described in application Serial No. 693,116, now Patent No. 1,995,730. Also, like the unit of Figs. 1 to 5, the unit of Figs. 6 and 7 is 55 provided with a wire bail 91 pivotally secured to the lower side of the cover plate, as disclosed in application Serial No. 476,776, this wire bail 91 in the illustrated machine having a lower extension 92 connected to suitable winding stopping mechanism. The nature of such winding stopping mechanism will of course vary with the type of winding machine and is no part of the present invention, nor is it essential for the 60 purposes of the present invention that the wire bail 92 be employed to actuate winding stopping mechanism. In both winding units illustrated in this application, the winding stopping mechanism, which is that of my application Serial 65 No. 476,776, includes a crank 94 fastened to the 70 package-carrying arm and adapted to be turned by a lifter rod 95 which in turn is actuated by a crank 96 fastened to a shaft 97. A head 98 on the inner end of shaft 97 carries a pivoted dog 99, which is adapted to be detained by a pro- 75

jection from the upper rail 12, thus to turn the member 98, shaft 97, crank 96 and thereby raise the lifter rod 95 and lift the package 21 from the drive roll 26. A wire link 101 connects the lower extension 92 of the wire bail 91 with the pivoted dog 99, so that when the wire bail 91 is held down by the winding strands (as indicated in Fig. 2) the dog 99 in Fig. 6 is held out away from the rail 12 and a series of projections therefrom, whereas when the wire bail 91 is in an elevated position (Fig. 6), the dog 99 hangs free.

For the purpose of controlling the strand detecting and breaking mechanism, the bail wire 91 is extended beneath the cover plate at 103 (Fig. 7), bent upward to extend through a hole 104 in the plate, and thence downwardly at 105 to a point over the pivoted detector element 50, where it terminates in a flattened element 106 adapted to check the tilting of member 50 in the same general manner as the strip 86 of Figs. 1 to 5. Fig. 6 shows the winding package 21 in the act of being lowered into contact with the driving roll 26. In this position, the wire bail 91 is in its elevated position, and the member 106 lies close to the pivoted detector element 50 and prevents the latter from tilting beyond the position of Fig. 5. The system of linkage comprising the members 91, 92, 101, 99 and the extension 105 and terminal member 106, has a substantial inertia and resists depression of the bail wire 91, so that the package 21 winds on a substantial quantity of strand before the bail wire 91 is depressed to running position and the pivoted detector element 50 consequently released from the restraining effect of the element 106. During this interval, either strand *x* or *y* not already in its slot 43 or 44, can be pulled into such slot by the rotating winding package and the detector element 50 thereby put in balance.

A further utility of this mechanism will be apparent. When the package 21 is off the drive roll during a stoppage in winding, removal of one of the strands from the detector, and tensioning the other strand will leave such other strand retained in the detector, since the element 106 prevents the detector element 50 from releasing. It will be apparent that this operation is not dependent upon travel of the units, or the particular type of package lifting and lowering mechanism illustrated, but that the invention is of general applicability to doubling and like machines having mechanism responsive to the absence of a strand.

It will be apparent that both in the embodiment of Figs. 1 to 5 and in the embodiment of Figs. 6 and 7 the machine includes a stop means which is operative at times to prevent the action of the strand-severing means, and that there is relative movement in timed relation between the strand-severing means and a part of the stop means, this relative movement being exemplified in the movement of the traveling winding unit with respect to the strip 86 in the embodiment of Figs. 1 to 5 and in the movement of the arm 105 of the wire bail 91 with respect to the unit on which it is mounted in Figs. 6 and 7.

In the claims, reference to severance of a strand is intended to include either cutting, breaking or any type of rupture.

I claim:

1. A textile machine including means for wind-

ing a plurality of strands, means for causing severance of one of said strands upon the failure or absence from said means of another of the strands, and means for preventing operation of said last-named means, the machine including means responsive to the winding strand for automatically rendering the said preventing means ineffective only upon the lapse of an interval of time after winding has begun. 5

2. A textile machine including means for winding a plurality of strands, means for causing severance of one of said strands upon the failure or absence from said means of another of the strands, and means for preventing operation of said last-named means, the machine including 10 means, including conveying means causing the winding means and severance-causing means to travel out of cooperative relation to the said preventing means, for automatically rendering the said preventing means ineffective only upon 15 the lapse of an interval of time after winding has begun. 20

3. A textile machine including means for winding a plurality of strands, a multiple strand detector including an element adapted to respond 25 to the absence of either of said strands, and means for preventing operation of said element, the machine including means responsive to the winding strand for automatically rendering the 30 said preventing means ineffective only upon the lapse of an interval of time after winding has begun.

4. A textile machine including means for winding a plurality of strands, a multiple strand detector including an element adapted to respond 35 to the absence of either of said strands, and means for preventing operation of said element, the machine including means, including conveying means causing the winding means and multiple strand detector to travel out of cooperative 40 relation to said preventing means, for automatically rendering the said preventing means ineffective only upon the lapse of an interval of time after the winding has begun.

5. A textile machine having strand winding 45 means for winding a plurality of strands, guide means for a plurality of strands to be wound, severing means operative to cause severance of one of said strands upon absence of another of the strands from the guide means, stop means 50 operative at times to prevent action of the severing means, said stop means including a part which moves relatively to the strand winding means and in timed relation thereto, the stop means being constructed and arranged to become 55 inactive only after the lapse of an interval of time after effective operation of the winding means begins.

6. A textile machine including means for winding a plurality of strands, a multiple strand detector including an element adapted to respond to the absence of either of said strands, stop means operative at times to prevent action of the detector element, said stop means including a part which moves relatively to the strand 60 winding means and in timed relation thereto, said stop means being constructed and arranged to become ineffective only upon the lapse of an interval of time after effective operation of the winding means begins. 65

EDWARD J. ABBOTT.
